UNITED STATES PATENT OFFICE.

HANS GOLDSCHMIDT, OF ESSEN-ON-THE-RUHR, GERMANY, ASSIGNOR, BY MESNE ASSIGNMENTS, TO GOLDSCHMIDT DETINNING COMPANY, OF NEW YORK, N. Y., A CORPORATION OF NEW JERSEY.

APPARATUS FOR DETINNING TIN SCRAP, BOXES, OR THE LIKE.

1,139,410.

Specification of Letters Patent. Patented May 11, 1915.

Application filed December 24, 1906. Serial No. 349,350.

To all whom it may concern:

Be it known that I, HANS GOLDSCHMIDT, a subject of the King of Prussia, German Emperor, and resident of Essen-on-the-5 Ruhr, Kingdom of Prussia, German Empire, have invented certain new and useful Improvements in Apparatus for Detinning Tin Scraps, Boxes, or the like, of which the following is an exact specification.

10 It is the purpose of my invention to detin tinned scraps of all kinds also old tin boxes and similar matter in an alkaline bath by means of an electric current, where the tinned scraps are packed in a certain number of baskets, the baskets being made of 15 perforated sheets or screens and, in so far as concerns the capacity of containing within themselves the material to be detinned, closed on all sides. They are fastened to an 20 endless band or chain, the lower part of which with the number of baskets attached to it is carried through an electrolyzing bath. In combination with this endless band and with the baskets fixed to it an 25 arrangement is provided to have the cathodes attached to a rotating endless band also, and carry them in a like manner through the electrolyzing bath, instead of being arranged in single stationary plates as 30 is common.

As a matter of course the endless band or chain which holds the baskets has to be properly insulated and connected with the positive pole of the dynamo, whereas the 35 cathodes either directly or by means of the slide- or guide-rail are connected with the negative pole of the machine.

In order to make my invention better understood I have illustrated the same by 40 drawings, in which:

Figure 1 shows a sectional side-view of a constructional form of the apparatus, Fig. 2 represents a longitudinal section of the same apparatus on the line *a*—*b*, Fig. 1, 45 and Fig. 3 is a similar view on the line *c*, *d*, Fig. 4 a diagram showing the electric connection and current-distribution of six baths in series connected to two unipolar dynamos in parallel, Fig. 5 is a view showing the 50 electrical connections to the anode baskets and cathode plates; also means for removing the anode baskets from the carrying chains and removable cover for said baskets,

Fig. 6 illustrates the resilient means for pressing the rollers *M*, *M'*, against the cathode plates. 55

In the drawing *A* represents the tank or vat, that contains the electrolyzing solution. Submerged in this bath are the baskets *B* which hold the tin scraps to be detinned. 60 The baskets are closed on all sides in order to hold the scraps more securely while passing through the bath. In order to give the solution a good chance to get in close touch with each tin scrap, the walls of the baskets 65 have to be made of perforated sheets or of screens, that allow the solution to freely pass therethrough. The basket is attached to an *I*-sectioned endless band *C* in form of a chain. Within the tank this endless 70 chain is guided by rails *F* attached to the cover of the tank, which outside of the tank assume the form of channels. This guide *F* must be connected electrically and made of conductive material to serve the purpose of 75 conducting the electric current to the baskets, forming the anode. From some suitable place of these guide-rails *F* a cable connection goes to the positive pole of the machine, as indicated by *G* on Fig. 1. The 80 cathodes formerly arranged in plates and suspended from rods into the bath are according to my invention arranged in plates attached to an endless band *H*. The plates are marked *D* on the drawings. This endless band *H* is made in similar chain-like 85 form as the one used for the basket, and also of conductive metal to serve as conductor of the current and to connect the cathodes to one another. Within the bath the 90 chair, is guided on rails *K* that form the shape of a channel outside of the bath. Over this channel and outside of the bath are standards or supports *L* on which are mounted pairs of compression rollers *M*, *M'* 95 made of non-conducting material, for instance marble, hard-rubber, or glass. The compression may be effected by means of any suitable compression mechanism, for instance short plates, pressing against the 100 cathode. The cathodes pass between these rollers or plates thus positioned that they compress the tin which is attached to these plates as they leave the bath in a spongy form. The pairs of rollers *M*, *M'* must 105 allow a side motion in order to give way

for an increased thickness of the tin on the cathodes as the latter return from each submersion in the bath.

The guide-rails K should also be made of 5 conductive material and in continuous connection with one another, for they are to serve as a conductor for the electric current to the cathode-plates. The rails are to be connected at some suitable place with the 10 negative pole of the dynamo indicated on the drawing by N. To impart the desired motion to the three endless chains carrying the baskets and the two rows of the cathode-plates, friction rollers have to be provided 15 for these chains. In order to avoid a short circuit between the anodes (baskets) and the cathodes (plates) care must be taken to have these rollers either made of insulating material or have them properly insulated 20 from the shaft, or to have these insulated rollers arranged on separate shafts each.

On Figs. 1 and 2 this mechanical arrangement of rollers for the movement of chains is indicated on the drawing by O 25 and O' which move the center endless chain to which the baskets are attached. The rollers P and P' and P² and P³ move the two endless chains to which the cathode plates are fixed. These rollers are keyed to 30 shafts and connected to one another by the belts or gear-wheels and are driven from an outside source of power, for instance, as shown on the drawing, by means of a belt attached to a loose and fixed pulley-arrangement Q.

In Fig. 4 six bath tanks A', A², A³, A⁴, 40 A⁵, A⁶ are shown, and connected in series by cross connections R. These connections must be arranged as shown in order to accomplish 45 an even distribution of the current. The two dynamos of unipolar type T T' are connected in parallel; such an arrangement for instance would suffice for a current of 14 to 17 volts and 15,000 amperes capacity.

An essential feature of my invention is the possibility of disengaging the baskets as well as the cathode-plates from the endless chain. The cathode plates may be disengaged 50 as soon as the layer of tin is thick enough, and the layers may be scraped off or melted off as desired.

It must be mentioned that the scraps are placed into the baskets when the latter are 55 in the upright position, where the tin scraps can easily be packed into the baskets. Hereupon the baskets are closed with a perforated cover and submerged into the electrolytic bath. When the baskets come out 60 of the bath they are emptied when in their horizontal position. It is understood of course that the process requires a certain time for completely detinning the scraps and therefore it is evident that the baskets 65 are submerged several times continuously

and brought out of the bath by the endless chain as long as there is any tin left on the scraps.

Of course the method can be varied in such manner that the chain does not continuously rotate, but that the movement of the chain is stopped for a certain time and then is restarted. Naturally the movement of the baskets in the bath can be to and fro for a certain time and when the detinning has been completed the chain can be moved in such manner that the detinned baskets come out of the bath.

The length of the single bath may be about 30 meters, the width of the bath about 70 half a meter, the length and width of the baskets 75 35 centimeters, the length of the single cathode-plates may be the same as the length of the single baskets.

Having thus fully described the nature of 80 my invention, what I desire to secure by Letters Patent of the United States is:—

1. An apparatus for detinning tin-scaps, 85 boxes or the like in an electrolytic bath, comprising anodes and cathodes movable in 90 a circuit into and out of the bath, and baskets carried by the anodes for containing the articles to be detinned.

2. An apparatus for detinning tin-scaps, 95 boxes or the like in an electrolytic bath, comprising anodes and cathodes movable in a circuit into and out of the bath, baskets carried by the anodes for containing the articles to be detinned, and means extraneous the bath arranged to engage and compress the spongy tin collected 100 on the cathodes.

3. An apparatus for detinning tin-scaps, 105 boxes or the like in an electrolytic bath, comprising anodes and cathodes movable in a circuit into and out of the bath, baskets carried by the anodes for containing the articles to be detinned, and adjustable means extraneous the bath arranged to engage and compress the spongy tin collected 110 on the cathodes.

4. Apparatus for detinning tin-scaps, 115 boxes, or the like in an electrolytic alkaline bath, characterized by cathode-plates continuously movable in a circuit into and out of said bath, in combination with rollers for compressing the spongy tin.

5. Apparatus for detinning tin-scaps, 120 boxes or the like in an electrolytic alkaline bath, characterized by cathode-plates and anodes continuously movable in a circuit, in combination with a mechanism for compressing the spongy tin, the mechanism being insulated.

6. Apparatus for detinning tin-scaps, 125 boxes or the like in an electrolytic alkaline bath, characterized by cathode-plates and anodes continuously movable in a circuit and simultaneously into and out of said bath, in combination with a mechanism for 130

compressing the spongy tin on the cathodes, the part of the mechanism in direct connection with the cathode-plates being constructed of non-conductive material.

- 5 7. An apparatus for detinning tin scrap, boxes and the like, comprising an electrolytic alkaline bath, anode bearing baskets for holding said tin scrap, boxes and the like movable in a circuit, and a series of 10 cathode plates also movable in a circuit simultaneously with the anode bearing baskets.
8. An apparatus for detinning tin scrap, boxes and the like, comprising an electrolytic bath, anodes comprising said tin scrap, boxes and the like, a series of cathode plates movable in a circuit and into and out of 15 said bath, and means for compressing the metal deposited on the cathodes.
- 20 9. An apparatus for detinning tin scrap, boxes and the like comprising an electrolytic bath, anodes comprising said tin scrap, boxes and the like, and cathodes carried by endless belts movable in unison in 25 a circuit, said anodes and cathodes being immersed for a part of the circuit in said bath.
10. An apparatus for detinning tin scrap, boxes and the like comprising an electrolytic bath, anodes comprising said tin scrap, boxes and the like insertible in said bath, and cathodes mounted on an endless belt 30 movable in a circuit, said anodes and cathodes being immersed for a part of the circuit in said bath.
- 35 11. An apparatus for detinning tin scraps, boxes or the like, comprising an electrolytic alkaline bath, anode bearing baskets made of perforated material for holding said tin-scrap, boxes or the like movable in a circuit, and a series of cathode

plates also movable in a circuit simultaneously with the anode-bearing baskets.

12. An apparatus for detinning tin-scrap, boxes or the like, comprising an 45 electrolytic alkaline bath, a traveling carrier movable in a circuit, anode-bearing baskets made of perforated material removable attached to said carrier, and a series of cathode-plates also removably attached 50 to the carrier and insulated from the anode-baskets.

13. An apparatus for detinning tin-scrap, boxes or the like, comprising an electrolytic alkaline bath, anode-bearing 55 baskets made of perforated material for holding said tin-scrap, boxes or the like movable in a circuit, said baskets having closures to cover openings in the baskets through which the material is placed, and 60 a series of cathode-plates, also movable in a circuit simultaneously with the anode-bearing baskets.

14. An apparatus for detinning tin-scrap, boxes or the like in an electrolytic 65 alkaline bath, cathode-plates simultaneously movable in a circuit into and out of said bath, and anode-baskets for containing said tin-scrap, boxes or the like insulated from 70 said cathodes.

15. An apparatus for detinning tin-scrap, boxes and the like, comprising an electrolytic bath, anodes and cathodes movable in a circuit into and out of the bath and baskets carried by the anodes for containing the articles to be detinned. 75

In witness whereof I have hereunto set my hand in the presence of two witnesses.
